(57) **CLAIM**

The ornamental design for a portable wireless charging power bank, as shown and described.

DESCRIPTION

FIG. 1 is a front right perspective view of a portable wireless charging power bank showing my new design;

FIG. 2 is a rear perspective view thereof;

FIG. 3 is a front view thereof;

FIG. 4 is a bottom view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the portable wireless charging power bank that form no part of the claimed design.
